[57] CLAIM

The ornamental design for shoe lace elements, as shown and described.

DESCRIPTION

FIG. 1 is a perspective view of shoe lace elements showing my new design;

FIG. 2 is a top view thereof;

FIG. 3 is a front view thereof;

FIG. 4 is a right side thereof, wherein the left side view is a mirror image thereof;

FIG. 5 is a rear view thereof;

FIG. 6 is a bottom view thereof; and,

FIG. 7 is a perspective view of an alternate embodiment of the shoe lace elements.

The dotted line outline of a shoe shown in FIG. 1 and 7 is for illustrative purposes only and forms no part of the claimed design.
